(57) **CLAIM**

I claim the ornamental design for a pipette, as shown and described.

DESCRIPTION

FIG. 1 is a left side, top, and front perspective view of the pipette;

FIG. 2 is a left side elevation view thereof;

FIG. 3 is a rear elevation view thereof;

FIG. 4 is a front elevation view thereof;

FIG. 5 is a right side elevation view thereof;

FIG. 6 is a top plan view thereof; and,

FIG. 7 is a bottom plan view thereof.

The broken lines in the drawings are included for the purpose of illustrating portions of the pipette that form no part of the claimed design.
